DESIGN FOR A UTILITY FORK

John I. Michaels, Wichita, Kans.

Application April 23, 1945, Serial No. 119,153

Term of patent 14 years

(Cl. D39—1)

To all whom it may concern:

Be it known that I, John I. Michaels, a citizen of the United States, residing at Wichita, county of Sedgwick, State of Kansas, have invented a new, original, and ornamental Design for a Utility Fork, of which the following is a specification, reference being had to the accompanying drawing, forming part thereof, in which

Fig. 1 is a top plan view of a utility fork showing my new design,

Fig. 2 is a rear view thereof, and

Fig. 3 is a side view.

I claim:

The ornamental design for a utility fork, substantially as shown.

JOHN I. MICHAELS.
